UNITED STATES PATENT OFFICE.

CHARLES R. KITTLE, OF LOS ANGELES, CALIFORNIA.

HYDROCARBON-BURNER.

SPECIFICATION forming part of Letters Patent No. 605,200, dated June 7, 1898.

Application filed October 7, 1897. Serial No. 654,484. (No model.)

To all whom it may concern:

Be it known that I, CHARLES R. KITTLE, a citizen of the United States, residing in the city and county of Los Angeles, State of California, have invented new and useful Improvements in Hydrocarbon-Burners, of which the following is a specification.

My invention relates to hydrocarbon-burners for using oil and steam; and it consists of the novel construction hereinafter set forth and claimed.

The object of my invention is to provide a burner of simple construction, adapted to introduce oil and steam into the furnace under full pressure at the point of their outlet from the burner and to provide for their regulation at this point. I attain these objects by the mechanism illustrated in the accompanying drawings, in which

20 Figure 1 is a longitudinal vertical section of my burner; Fig. 2, a plan view of the oil-regulating valve or disk; Fig. 3, a perspective view of the steam-regulating valve with the stem partly cut away.

25 Referring primarily to Fig. 1, A represents the body or frame of the burner. Into the upper end thereof is screwed the cap B, having therein a recess for the insertion of the end of the stem of the disk D and spiral spring

30 V. Into the other end is screwed the cap B', having a recess therein for the insertion of the stem of the valve J and a set-screw L to keep said valve in contact with its seat. Into the side of the frame A is screwed the oil-supply pipe R and below it the steam-supply pipe

35 T. At a point sufficiently distant from the point of combustion that the heat may not interfere with the operator these pipes turn so as to permit of the passage therethrough of stems with handles thereon for operating the disk D and valve J. The stem I passes through the oil-supply pipe and through the frame A and terminates in a crank-pin I'. Above the stem I in the frame A is placed one or more

40 orifices II' for the passage therethrough of oil. In the front of the frame A, forming the seat of the valve or disk D, is one or more ports F for the outlet of oil into the main discharge-port U. In the upper part of the frame A is

45 placed the valve or disk D, with a stem entering the recess in the cap B. Above the stem is placed a spiral spring V to keep the valve

or disk D in close contact with its seat. On one side of the disk D are lugs E E, which engage with the crank-pin I'. The disk D has 55 one or more orifices II for the passage therethrough of oil, which will register, when open, with the ports F in the valve-seat. In the lower part of the frame A is formed the steam-valve seat and near the top thereof is the 60 steam-port K, leading therefrom to the main discharge-port U. In this seat is placed the valve J, having stem J'' and one or more orifices J' for the passage therethrough of steam. The top of the valve J terminates in a spiral, 65 as shown in Fig. 3. By this spiral top when the valve is rotated the port K is partially or wholly closed or left open. On the lower part of the valve-stem J'' is placed a bevel gear-wheel M, which meshes with the wheel on the 70 stem P. The end of the stem J'' where it enters the recess in the cap B' is circular. On the end of the stem P is placed the bevel gear-wheel N, meshing with the wheel M. Above the stem P is one or more orifices K' 75 for the passage therethrough of steam. The number and size of the orifices H, H', J', and K' and ports F and K are governed by the maximum capacity of the burner.

The operation of my device is as follows: 80 The burner is placed in a furnace and connected with a steam and oil supply, with the ports F and K closed. The valves D and J are then rotated by means of their respective stems, so as to admit a sufficient quantity of 85 oil and steam to pass through these ports to produce combustion, and the fire started. The oil coming down through the ports F is caught by the steam issuing through the port K under full pressure and atomized, thereby 90 forming a suitable fuel for burning. As the quantity of oil and steam is regulated at the point of outlet from the burner it will be observed that as soon as there is a steam-pressure 95 in the boiler sufficient to atomize a very small quantity of oil my burner can be used. I have found from experience that I can use it with as low a pressure as three pounds.

Another advantage of my burner is that no matter of how large a maximum capacity 10: the burner may be it can be operated to produce a minimum fire without any danger of blowing out. This is due to the fact that the oil and steam are always under full pressure

at the point of outlet from the burner. I have shown what I consider to be the best means for regulating the oil and steam at the point of outlet from the burner, but do not desire to confine myself to these specific devices, as it is apparent that there are many other devices which may be employed for the same purpose.

Having thus described my invention, what I claim as new, and desire to secure by Letters Patent, is—

1. A burner comprising a body portion having an oil-chamber in its upper part, a steam-chamber in its lower part, a vertical oil-discharge port, and a horizontal steam-discharge port, the steam-discharge port discharging across the axis of the oil-discharge port, in combination with a valve having a spiral at its top and arranged to govern the steam-discharge port, substantially as described.

2. In a hydrocarbon-burner, the combination with the frame, A, having main discharge-port, U, a horizontal steam-discharge port, K, and vertical oil-discharge port, F, leading to discharge-port, U, and arranged to cause the steam and oil discharged therefrom to intermingle at the main discharge-port, the frame having a chamber in the upper part thereof adapted to receive an oil-valve, and a chamber in the lower part adapted to receive a steam-valve; a rotary oil-valve, D, having oil-passages, II, located in the upper chamber; and rotary steam-valve, J, having steam-passages, J', and having spiral top, located in the lower chamber, the said valves rotatively operated by stems, I, and P, respec-

tively having means therefor substantially as shown and described.

3. A burner, comprising a body portion having an oil-chamber in its upper part; a steam-chamber in its lower part; a vertical oil-discharge port and a horizontal steam-discharge port, the oil-discharge port discharging across the axis of the steam-discharge port, in combination with the rotary valve D, being in the form of a disk having passages therethrough adapted to register with the oil-discharge port and thereby govern the discharge of oil, substantially as shown and described.

4. A burner, comprising a body portion having an oil-chamber in its upper part; a steam-chamber in its lower part; a vertical oil-discharge port; and a horizontal steam-discharge port, both discharging into a main discharge-port, adapted to mingle the oil and steam at the mouth of the main discharge-port, in combination with a conical-shaped valve being spiral at the top and having passages therethrough and arranged to govern the steam-discharge port, substantially as shown and described.

5. In a burner, comprising a body portion having oil and steam chambers; oil and steam discharge ports, the cone-shaped valve, J, having a spiral top, and having passages, J' therethrough for the passage of steam and arranged to govern the steam-discharge port, substantially as shown and described.

CHARLES R. KITTLE.
